HEEL HOLDER FOR HEEL-ATTACHING
MACHINES

John T. Lancaster, Newton, Mass., assignor to
United Shoe Machinery Corporation, Borough
of Flemington, N. J., a corporation of New
Jersey

Application May 17, 1940, Serial No. 335,728

22 Claims. (Cl. 1—32)

My invention relates to machines for attaching heels to shoes, having particularly to do with the simultaneous nailing to a shoe of separate heel-sections, as a base-section and a tread-section or lift, the latter being usually of rubber.

In Letters Patent of the United States No. 1,723,310, Standish, August 6, 1929, is disclosed a heel-holding mechanism, in which there is a carrier movable between an active position over the nailing die of a heelng machine and an inactive position at one side thereof. Upon this carrier is a lower holder or ring to receive and retain against expansion a rubber lift and an upper holder, consisting of a pair of fingers between which a heel-base may be inserted for vertical registration with the lift in the ring. These fingers are forced toward each other by a spring, so they will grasp the base securely. In introducing a base, the operator must use some effort to separate the fingers by direct engagement with them. An object of this invention is to relieve the operator of the necessity for direct manipulation of such grasping members.

In the achievement of this object, with a nailing die and other elements of nail-driving mechanism and mechanism for transferring nails to the nailing mechanism, and a holder in which plural heel-sections are presented one above another for simultaneous attachment, and including members movable to grasp a heel-section, I associate means movable under the influence of an element of the machine for separating the grasping members. This element for thus controlling movement of the members is preferably included in one of the mechanisms which acts upon the nails, it being herein shown as a part of the nail-transferring mechanism. When, for example, the base-grasping fingers are separated in this manner as an incident to another act which the operator must perform, the effort required is negligible, and no thought need be given to it. In their open relation, the grasping members are latched against the action of a spring loaded by means movable under the influence of an element of the machine, and there is means for releasing them to close upon an applied heel-section. Both the separation of the members and their release is effected by means fixed relatively to the movable holder, the releasing means being preferably adjustable in position to permit the operator to vary the time at which the applied heel-section is grasped. With the grasping members or fingers, there is combined, in the structure of the previously mentioned patent, means for adjusting their normal separation, and, as

shown herein, the separating means of the present invention engages this adjusting means. In the illustrative embodiment of the invention there is employed a rod connected to the fingers, together with the adjusting means for varying the extent of movement of said rod, and means, as a lever, fulcrumed upon the carrier for the fingers and movable in engagement with the adjusting means to separate said fingers. Since the fingers are preferably adjustable upon their carrier, a portion of the lever may be variable in length to compensate for this. A plunger is movable in the carrier, and, upon contact with a relatively fixed member, causes the finger-actuating oscillation of the lever during the travel of the carrier. A latch for the plunger maintains the fingers temporarily separated, and may be released by its engagement with a member which may be fixed in different positions relatively to said latch.

In the accompanying drawings:

Fig. 1 is a top plan view of a particular embodiment of my invention;

Fig. 2, a vertical section on the line II—II of Fig. 1;

Fig. 3, a similar view on the line III—III of Fig. 1, looking in a direction opposite to that of Fig. 2;

Fig. 4, a like view on the line IV—IV of Fig. 3; and

Fig. 5, a sectional detail on the line V—V of Fig. 1.

At 10 appears a frame upon which is mounted the nailing die 12 of a heelng machine. Reciprocatory drivers 14 operate in passages in the die to insert the nails, which they carry, through a lower lift L of such yieldable material as rubber and a leather or like base H, into the heel-seat of a shoe S supported upon a jack 16. The lift and base are presented to the nailing mechanism by a double holder, of the character of that disclosed in the patent previously referred to, and which need only be described briefly. A carrier 18 is guided for horizontal travel above the die 12 by means including a rod 20, fixed at one extremity to the frame 10 and at the other to a bracket 22 projecting from said frame. In the lower portion of the holder, forms or rings 24 may be mounted interchangeably in ways, the opening in each ring being of the proper shape to receive and hold against expansion a particular size of lift. The base, applied above the lift in the ring, is grasped between opposite fingers 26, 26, respectively pivoted at 28, 28 upon a support 29, and geared together at 27. This

support is mounted for vertical tilting adjustment upon a slide 30 variable in position from front to rear of the carrier 18. The fingers are urged toward each other to assume their closed relation by an expansion-spring 32, interposed between a projection 34 from one of the fingers and a bracket 36 secured to the support 29. The spring surrounds a rod 38 pivoted to the projection 34 and passing through an opening in the bracket 36. A nut 40, threaded upon the rear end of the rod, limits adjustably its forward movement under the influence of the spring, and, therefore, the normal separation of the fingers. These fingers 26 are hooked at their extremities, as shown at 42, to engage the breast-corners of the applied base and locate it above the lift, as it is forced forward by a fork 44 contacting with opposite sides of the rear of the base and yieldably advanced by an expansion-spring 46, acting upon a supporting shank 48. For the fingers are provided various adjustments, by which they may be located properly for the base being operated upon. In the present connection, it is unnecessary to particularly consider these adjustments. The holder, consisting of the carrier with the lift- and base-retaining means, is movable upon its supports between an active position over the die 12, as illustrated in Fig. 1, to the left of the machine to free the die for the reception of the attaching nails. This movement is effected by contact with an arm 50 connected with a latch 52, which releasably retains the holder in operating position, of the usual oscillatory arm 54, when this is swung inwardly by the operator to transfer a load of nails supplied to it to the die.

Considering now the elements peculiar to this invention, there is attached to the carrier 18 a bracket 60, in which is guided for vertical movement an actuating plunger 62. Pivoted to this plunger at 64 is a horizontally extending rod 66, which, in effect, furnishes one arm of a bell-crank-lever. The other arm 68 of the lever projects upwardly from a horizontal spindle 70, rotatable in a downward extension 72 of the bracket 36 and having a generally horizontal portion 74, through a bore in which the rod 66 is free to shift longitudinally. This variation in the length of the lever-arm compensates for the adjustment of the slide 30 upon the carrier 18 and the consequent relative movement between the brackets 36 and 60. The upper extremity of the arm 68 is forked to receive the rod 38 and lies in contact with the bracket 36, being held against it by the adjusting nut 40 under the influence of the spring 32. When the base- and lift-holders are caused to travel to the left, upon the actuation of the loader-arm 54 by the operator, a roll 76 upon the bottom of the plunger 62 engages an upwardly and outwardly inclined cam-surface 78 upon a controlling member 80, mounted upon the frame of the die. This occurs immediately after the holder leaves its normal position. The cam elevates the plunger, rocking the bell-crank-lever 66, 68 anticlockwise, as viewed in Fig. 3. The lever-arm 68 is thereby forced against the adjusting nut 40, drawing the rod 38 to the left, loading the spring 32 and opening the fingers 26, ready for the insertion of the heel-base. The member 80 is pivoted at 77, with its surface 78 held normally in the path of the roll 76 by a leaf-spring 79 secured to the frame. A pin 81, rising from the frame into an arcuate slot in the member, limits the pivotal movement in an anticlockwise direction (Fig. 1). This causes the cam-surface to act upon the plunger during 75

travel of the holder away from the nailing die, while the member yields to avoid interference with the plunger during the return movement.

Pivoted upon the outer end of the bracket 60, adjacent to the plunger 62, is a latch 82, the upper end of which is urged by an expansion-spring 84 interposed between it and the bracket against a horizontal extension 86 from the plunger. As the plunger is lifted by the cam, 10 the latch passes beneath the extension to temporarily retain the plunger raised and the fingers 26 separated. Now, as the holder travels in either direction, the operator may insert a base between the fingers. Said fingers are released 15 to grasp the base for the attaching operation by the action of tripping means. Parallel to the guide-rod 20, and fixed in projections from the bracket 22, is a rod 90, along which a collar 92 may be clamped at any chosen point by a set-screw 94. From the outer side of the collar is 20 an extension 96, upon which is pivoted for horizontal oscillation an arm 98. The arm is held yieldably in a normal position against the collar by a leaf-spring 100, secured to the extension 25 and resting against the arm. Upon the upper side of the arm is a cam-surface 102 inclined downwardly and outwardly. Projecting rearwardly from the latch 82 is a horizontal pin 104, and mounted for vertical reciprocation in the bracket 60, in a position below the pin when the fingers 26 are latched open, is a tripping plunger 106, having at its upper extremity a conical surface 108. The lower end of the plunger 106 is preferably rounded at 110. In the movement 30 of the holder to the left, or away from the nailing die, the end 110 of the plunger 106 strikes the tripping arm 98 and forces it aside, the spring 100 yielding. In the return of the holder, the plunger-end 110 engages the surface 102 of the arm 98, now held against yield. This surface cams up the plunger, the surface 108 of which strikes the latch-pin 104. The latch is thereby shifted from beneath the extension 86 of the actuating plunger 62, freeing this, so the spring 40 45 32 may close the fingers upon the applied base. The plunger is also lowered by the spring, and when it reaches the controlling member 80, forces this idly aside against the spring 79.

As to the operation of the holder, it may be said that, with the jack 16 in its outer raised position, the operator will insert a tread-section or lift L in the ring 24, and with his right hand swing in the arm 54, its block carrying a load of nails to deliver to the passages in the die 12. 50 The loader-arm, engaging the arm 50, first unlatches the holder at 52, and then forces said holder away from the die along the guide-rod 20 to a distance sufficient to allow the nails to drop from the loader-block into the die-passages. Early in the travel of the holder, the relatively fixed cam 78 lifts the actuating plunger 62 and, through the bell-crank-lever 66, 68 and holder-rod 38, separates the fingers 26, which are at once latched open by the member 82 against the force of the now loaded spring 32. A base-section H of the heel, which the operator has taken in his left hand, may, at any time in the further advance of the holder or the return to its active or attaching position, be placed upon the previously applied lift, the rear fork 44 being slightly pressed back against its spring 46. Then the lift is freed to be urged by the spring against the hooks 42 of the fingers 26. According to the preference of the oper-

ator as to the time of insertion of the base, the tripping arm 98 will have been set at such a position along the rod 90, that its surface 102 will be effective to lift the plunger 106 just as the operator's hand frees the base. The actuating plunger 62 is thereby released, and the spring 32 causes the fingers to grasp the base and restores the plunger 62 to its initial lowered position. Under these conditions, said base is at once correctly located by the fingers and held against displacement during the completion of its travel and the attaching operation. It will be seen that this means for opening and closing of the fingers calls for no attention or direct effort on the part of the operator, and that it is accomplished without alteration of or interference with the action of any part of the holder with which it is combined.

Having described my invention, what I claim as new and desire to secure by Letters Patent of the United States is:

1. In a heel-attaching machine, nail-driving mechanism, mechanism for transferring nails to the driving mechanism, a holder having devices by which plural heel-sections are arranged for presentation one above another to the nailing mechanism for simultaneous attachment, one of said devices being provided with movable members between which a heel-section is grasped, and means movable under the influence of an element of the machine for separating the grasping members from each other.

2. In a heel-attaching machine, nail-driving mechanism, mechanism for transferring nails to the driving mechanism, a holder having devices by which plural heel-sections are arranged for presentation one above another to the nailing mechanism for simultaneous attachment, one of said devices being provided with movable members between which a heel-section is grasped, and means movable under the influence of one of the mechanisms acting upon nails for separating the grasping members from each other.

3. In a heel-attaching machine, nail-driving mechanism, mechanism for transferring nails to the driving mechanism, a holder having devices by which plural heel-sections are arranged for presentation one above another to the nailing mechanism for simultaneous attachment, one of said devices being provided with movable members between which a heel-section is grasped, means for separating the grasping members for the reception of a heel-section, means for latching the grasping members in their separated relation, and means for releasing the grasping members to close upon an applied heel-section.

4. In a heel-attaching machine, nail-driving mechanism, mechanism for transferring nails to the driving mechanism, a movable holder provided with members for grasping a heel to be nailed, and means movable under the influence of the transferring mechanism for separating the grasping members.

5. In a heel-attaching machine, nail-driving mechanism, mechanism for transferring nails to the driving mechanism, a movable holder provided with members for grasping a heel to be nailed, means movable under the influence of the transferring mechanism for separating the grasping members, and means acting in the movement of the holder for closing the fingers.

6. In a heel-attaching machine, nail-driving mechanism, mechanism for transferring nails to the driving mechanism, a movable holder pro-

vided with members for grasping a heel to be nailed, means movable under the influence of the transferring mechanism for separating the grasping members, means movable with the holder for latching the grasping members in their separated relation, and means into engagement with which the latching means is moved to release the grasping members.

7. In a heel-attaching machine, a nailing die, a heel-holder having a carrier with heel-grasping fingers movable into and out of co-operation with the die, an actuating member movable upon the carrier, a lever fulcrumed upon the carrier and engaged by the actuating member, a connecting member between the lever and fingers, and a relatively fixed member by which the actuating member is moved in the travel of the carrier.

8. In a heel-attaching machine, a nailing die, a heel-holder having a carrier with heel-grasping fingers pivoted thereon and movable into and out of co-operation with the die, an actuating member movable upon the carrier, a lever fulcrumed upon the carrier and engaged by the actuating member, a connecting member between the lever and fingers, a relatively fixed member by which the actuating member is moved in the travel of the carrier to separate the fingers, a latch mounted upon the carrier and engaging the actuating member to temporarily maintain the separation of the fingers, and a member fixed relatively to the carrier and engaging the latch to release the fingers.

9. In a heel-attaching machine, a nailing die, a heel-holder having a carrier with heel-grasping fingers pivoted thereon and movable into and out of co-operation with the die, an actuating member movable upon the carrier, a lever fulcrumed upon the carrier and engaged by the actuating member, a connecting member between the lever and fingers, a relatively fixed member by which the actuating member is moved in the travel of the carrier to separate the fingers, a latch mounted upon the carrier and engaging the actuating member to temporarily maintain the separation of the fingers, a member fixed relatively to the carrier and engaging the latch to release the fingers, and means arranged to fix the releasing member in position to act upon the latch at different times in the travel of the carrier.

10. In a heel-attaching machine, a nailing die, a heel-holder having a carrier with heel-grasping fingers movable into and out of co-operation with the die, means acting upon the fingers to adjust their normal separation, and means engaging the adjusting means to separate the fingers.

11. In a heel-attaching machine, a nailing die, a heel-holder having a carrier with heel-grasping fingers movable into and out of co-operation with the die, means acting upon the fingers to urge them normally toward their grasping position and to adjust their normal separation, and means engaging the urging and adjusting means to separate the fingers.

12. In a heel-attaching machine, a nailing die, a loader movable to deliver nails to the die, a carrier normally situated above the die and movable therefrom by the loader, a holder for a tread-section of a heel mounted upon the carrier, a pair of fingers pivoted upon the carrier above the holder to grasp a base-section of a heel, a spring acting to close the fingers, and means movable under the influence of an element of the machine for loading the spring.

13. In a heel-attaching machine, a nailing die, a loader movable to deliver nails to the die, a

carrier normally situated above the die and movable therefrom by the loader, a holder for a tread-section of a heel mounted upon the carrier, a pair of fingers pivoted upon the carrier above the holder to grasp a base-section of a heel, a spring acting to close the fingers, means movable under the influence of an element of the machine for loading the spring, a latch for retaining the fingers open against the force of the loaded spring, and means for tripping the latch.

14. In a heel-attaching machine, a nailing die, a loader movable to deliver nails to the die, a carrier normally situated above the die and movable therefrom by the loader, a holder for a tread-section of a heel mounted upon the carrier, a pair of fingers pivoted upon the carrier above the holder to grasp a base-section of a heel, a spring acting to close the fingers, a rod connected to the fingers, adjusting means arranged to vary the extent of movement of the rod under the influence of the spring, and means movable in engagement with the adjusting means to separate the fingers.

15. In a heel-attaching machine, a nailing die, a loader movable to deliver nails to the die, a carrier normally situated above the die and movable therefrom by the loader, a holder for a tread-section of a heel mounted upon the carrier, a pair of fingers pivoted upon the carrier above the holder to grasp a base-section of a heel, a spring acting to close the fingers, a rod connected to the fingers, a member variable in position upon the rod to limit its movement under the influence of the spring, a lever fulcrumed upon the carrier and engaging the limiting member, and means acting in the movement of the carrier to oscillate the lever.

16. In a heel-attaching machine, a nailing die, a loader movable to deliver nails to the die, a carrier normally situated above the die and movable therefrom by the loader, a holder for a tread-section of a heel mounted upon the carrier, a pair of fingers pivoted upon the carrier above the holder to grasp a base-section of a heel, a spring acting to close the fingers, a rod connected to the fingers, a member variable in position upon the rod to limit its movement under the influence of the spring, a lever fulcrumed upon the carrier and having relatively movable arms, one of which engages the limiting member, and a member fixed relatively to the carrier and acting upon the other arm of the lever.

17. In a heel-attaching machine, a nailing die, a loader movable to deliver nails to the die, a carrier normally situated above the die and movable therefrom by the loader, a holder for a tread-section of a heel mounted upon the carrier, a pair of fingers pivoted upon the carrier above the holder to grasp a base-section of a heel, a spring acting to close the fingers, a rod

connected to the fingers, a member variable in position upon the rod to limit its movement under the influence of the spring, a lever fulcrumed upon the carrier, a plunger movable in the carrier in contact with the lever, and a member fixed relatively to the carrier and acting upon the plunger.

18. In a heel-attaching machine, a nailing die, a loader movable to deliver nails to the die, a carrier normally situated above the die and movable therefrom by the loader, a holder for a tread-section of a heel mounted upon the carrier, a pair of fingers pivoted upon the carrier above the holder to grasp a base-section of a heel, a spring acting to close the fingers, a rod connected to the fingers, a member variable in position upon the rod to limit its movement under the influence of the spring, a lever fulcrumed upon the carrier, a plunger movable in the carrier in contact with the lever, a member fixed relatively to the carrier and acting upon the plunger, a latch for the plunger movable upon the carrier, and a member arranged to be fixed in different positions relatively to the carrier for releasing the latch.

19. In a heel-attaching machine, a nailing die, a heel-holder having a carrier with heel-grasping fingers and movable into and out of co-operation with the die, a lever fulcrumed upon the carrier to move therewith and being connected to the fingers, and means for oscillating the lever.

20. In a heel-attaching machine, a nailing die, a heel-holder having a carrier with heel-grasping fingers movable into and out of co-operation with the die, a lever fulcrumed upon the carrier and connected to the fingers, means for oscillating the lever to separate the fingers, and a latch mounted upon the carrier and acting upon the fingers to temporarily maintain their separation.

21. In a heel-attaching machine, a nailing die, a heel-holder having a carrier with heel-grasping fingers adjustable in position upon the carrier and movable into and out of co-operation with the die, a lever fulcrumed upon the carrier and connected to the fingers, said lever having a portion variable in length to compensate for the adjustment of the fingers, and means for oscillating the lever.

22. In a heel-attaching machine, a nailing die, a heel-holder having a carrier with heel-grasping fingers adjustable in position upon the carrier and movable into and out of co-operation with the die, a lever fulcrumed upon the carrier and connected to the fingers, said lever having one arm movable upon another of its arms during the adjustment of the fingers, and means for oscillating the lever.

JOHN T. LANCASTER.
